UNITED STATES PATENT OFFICE.

JOSEPH N. WILSON, OF CHICAGO, ILLINOIS.

DESIGN FOR A CAMPAIGN-BADGE.

SPECIFICATION forming part of Design No. 33,408, dated October 23, 1900.

Application filed August 2, 1900. Serial No. 25,720. Term of patent 3½ years.

To all whom it may concern:

Be it known that I, JOSEPH N. WILSON, a citizen of the United States, residing at Chicago, Illinois, have invented and produced a new and original Design for a Campaign-Badge, of which the following is a specification.

In the accompanying drawings, Figure 1 is a front elevation with the center in perspective, illustrating my design; and Fig. 2, an edge view of the design.

A is a dinner-pail, and B the pictures or representations of faces thereon.

The leading feature of my design consists in a campaign-badge presenting in outline a dinner-pail A, having the picture or representation of human faces B thereon, the whole presenting an ornate and attractive appearance, as shown in the drawings.

I claim—

The design for a campaign-badge herein shown and described.

JOSEPH N. WILSON.
